UNITED STATES PATENT OFFICE.

FRED KONN, OF DENVER, COLORADO.

DESIGN FOR A VELOCIPED-E-SADDLETREE.

SPECIFICATION forming part of Design No. 27,307, dated July 6, 1897.

Application filed May 29, 1897. Serial No. 638,815. Term of patent 7 years.

To all whom it may concern:

Be it known that I, FRED KONN, a citizen of the United States of America, residing at Denver, in the county of Arapahoe and State of Colorado, have invented a certain new and original Design for Velocipede-Saddletrees; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to a new and original design for velocipede-saddletrees; and it consists of the features hereinafter described and claimed, all of which will be fully understood by reference to the accompanying drawings, 20 in which is illustrated an embodiment thereof.

In the drawings, Figure 1 is a top or plan view of a saddletree showing my new design. Fig. 2 is a section taken on the line xx , Fig. 1. Fig. 3 is a section taken on the line yy , Fig. 25 1, looking toward the left. Fig. 4 is a section taken on the line zz , Fig. 1, looking toward the top of the sheet.

As shown in the drawings, the leading or material feature of my design consists in the body of the saddletree, relatively wide as compared with its length, and providing the said tree with forwardly and downwardly extending projections 5^a , the tree being curved inwardly and its edge bent downwardly between said projections 5^a and the horn 6 , as shown at 5^c . The rear edge of the saddletree has an outwardly-curved or convex outline, as shown at 5^d , while the outline of the sides curves inwardly slightly, as shown at 5^e , and then outwardly to the projections 5^a . The 30 saddletree is further provided with an elongated central opening 7 .

Having thus described my invention, what I claim as new, and desire to secure by Letters Patent, is—

45 The design for a velocipede-saddletree as herein shown and described.

In testimony whereof I affix my signature in presence of two witnesses.

FRED KONN.
